UNITED STATES PATENT OFFICE.

EGBERT H. GOLD, OF CHICAGO, ILLINOIS.

HEATING SYSTEM.

1,204,562.

Specification of Letters Patent. Patented Nov. 14, 1916.

Application filed December 16, 1909. Serial No. 533,379.

To all whom it may concern:

Be it known that I, EGBERT H. GOLD, a citizen of the United States, residing at Chicago, in the county of Cook and State 5 of Illinois, have invented certain new and useful Improvements in Heating Systems, of which the following is a specification.

My invention relates to heating systems in which one or more of the control valves are 10 operated by a thermostat subjected to the influence both of the hot medium escaping from the system and to the temperature of the external atmosphere. Heating systems of this general character are shown and 15 claimed in my co-pending applications Serial No. 185,122, filed December 14, 1903, and Serial No. 245,311, filed February 11, 1905; the former application disclosing the inlet valve so controlled, the later applica- 20 tion, a system in which both inlet and outlet valves are automatically operated in the manner described.

The object of the present invention is to provide a novel form of heating apparatus 25 specifically different from those disclosed in the applications above referred to though operating upon the same general plan; the present invention providing a tubular thermostat for controlling the valve or valves 30 which may form a part of the pipe or conduit through which the water of condensation is discharged from the radiating pipes. It is not intended to claim herein the generic 35 inventions shown and described in applications Serial No. 185,122 and Serial No. 245,311.

The heating system of my present invention is particularly adapted for use in heating railroad trains.

40 The invention is illustrated, in a preferred embodiment, in the accompanying drawings in which—

Figure 1 shows a vertical sectional view through the controlling apparatus; and Fig. 45 2 is an enlarged detail showing in vertical section a modified or alternative arrangement of certain parts.

Like characters of reference indicate the 50 same parts in the several figures of the drawings.

A indicates the floor of a car, which may be, if desired, the usual double floor; B is the inlet pipe leading from the usual train pipe (not shown), which ordinarily 55 extends lengthwise beneath the car and between which and the pipe B the usual hand

operated valve (not shown) may be interposed, if desired, to manually disconnect the heating system of the car from the train pipe; C is the inlet port controlled by the 60 inlet valve D, which is mounted in an inlet chamber E. From the inlet chamber E pipe F leads to the radiating pipes in the car. The return end of the radiating system connects with the pipe G, which leads to the 65 discharge chamber H, from which the steam, or other heating medium, goes through the port I to the trap valve chamber J. Extending into the valve chamber J is the discharge or drip pipe K made, for 70 example, of brass or other metal having a relatively high co-efficient of expansion, the casing containing the various chambers above described being formed, for example, of iron, or other metal having a relatively 75 low co-efficient of expansion. The lower end of the discharge pipe K is open to the atmosphere and the pipe K is secured to a head L, which in turn is connected with the casing containing the trap valve chamber J in any suitable manner, as, for example, by means of iron rods M held in position by nuts N.

It will be seen that the brass tube or discharge pipe K passes through a familiar 85 form of stuffing box O and communicates, by means of openings P, with the interior of the trap valve chamber J. Preferably these openings P are so located as to be on a level with the bottom of the valve chamber J when the pipe K is contracted, so that any accumulating water of condensation 90 may escape freely from the chamber J through openings P into the pipe K and thence to the atmosphere. If the device, however, is to work to its best advantage, care should be had that the openings P are not so located as to communicate with the 95 external atmosphere in any position of the tube K when the device is in operation. The stuffing box O, while desirable, will not ordinarily be essential, but, by preventing the escape of any hot water or steam around the outside of the tube K, the stuffing box O will produce the best operation of the device for, when used, all escaping hot water and steam must flow through the interior of the discharge pipe K, thereby most effectively utilizing the heat of the escaping hot water and steam to expand the brass tube 100 or pipe K.

Where all features of my present inven-

tion are to be used, the port I will be fitted with a nipple R carrying a valve seat *r* and the spider or cap Q will carry a valve *g* so arranged that the expansion of the outlet 5 pipe K under the influence of escaping heating medium will cause the valve *g* to be seated on the valve seat *r*, but where this feature is not desired, the nipple R and the valve *g* may be omitted, as shown in the 10 modification appearing in Fig. 2.

Connected with the cap Q, whatever its form may be, is a stem S in operative engagement with the forked arm of a lever T, as, for example, by securing to the stem S 15 the collars *s*, *s*. The lever T is mounted on a spindle U interposed in the partition between chambers H and E in a familiar manner, as shown, for example, in my Patent No. 771,628, the spindle U being surrounded 20 by a stuffing box, if desired, and the arm of the lever T, which extends into the chamber E, is in operative engagement with the stem V of inlet valve D, as, for example, by forking the end of the lever T so as to surround 25 the stem V and providing the stem V with shoulders *v*, *v*.

When so arranged, the inflow of steam from the pipe B through the valve C, the chamber E, pipe F to the radiating system 30 and back through pipe G, chambers H and J and out through the thermostatic tube K to the atmosphere, will fill the system with steam and, expanding the thermostatic tube K, will rock the lever T and close or throttle 35 the inlet valve D, as the case may be. If the device is provided with the outlet valve *g* and valve seat *r*, they will be so arranged with relation to the other parts that the expansion of the tube K will simultaneously 40 close both the inlet and the outlet valves, whereupon the tube K, being exposed to the external atmosphere, will be quickly cooled as soon as the flow of steam or hot water therethrough is shut off and, promptly contracting, will admit more steam, thereby 45 forcing out any accumulated water of condensation, again contracting and throttling the inflow of steam, and so on, thereby keeping the system at all times filled with steam. 50 There need be no fear of buckling the tube K by expansion after the inlet valve is seated, because whenever the tube has expanded sufficiently to close the inlet valve, there will be no pressure behind the body of 55 heating medium in the radiating system and, therefore, no further outflow or further heating of the tube K.

In Fig. 2 I have illustrated how the device may be modified so as to omit the outlet valve, the parts being otherwise substantially the same as above described, the cap Q¹, differing from Q, Fig. 1, in omitting valve *g*. Preferably the cap Q¹ is formed with ports J¹ so that there will always be an outlet from the system. 60

I claim:

1. The combination with a heating system comprising a radiator and an inlet valve therefor, of a thermostat constituting a discharge conduit for said radiator, of operative connections between said thermostat and said inlet valve, said thermostat being provided with ports so located as to provide free passage for water of condensation from the system when the thermostat is contracted but so as to temporarily arrest the discharge of water of condensation when the thermostat is expanded. 70

2. The combination of a heating system comprising a radiator, an inlet valve therefor, a condensation chamber and a thermostat in operative connection with the inlet valve and consisting of an expansible tubing, serving as a discharge conduit from said condensation chamber and extending into the atmosphere, the outer end of said tubing being rigidly secured and the inner end thereof extending into said condensation chamber and provided with discharge ports so arranged as to drain said condensation chamber when the thermostat is contracted but to be wholly above the lowest point of said condensation chamber when said thermostat is expanded. 80

3. In a heating system, the combination with a radiator, an inlet valve therefor and a thermostat exposed to the discharge from said system and arranged to actuate said inlet valve, of means providing a condensation chamber interposed in said system and forming a part of the discharge conduit for water of condensation from said system, the part providing said condensation chamber having a portion thereof extending into the external atmosphere and means for so controlling the flow of water of condensation from said chamber that such flow will be intermittently arrested whenever the thermostat has been expanded by the medium discharged from said system. 95
